UNITED STATES PATENT OFFICE.

AVARD S. EMERY, OF NEW YORK, N. Y.; FRANCES O. EMERY ADMINISTRATRIX OF SAID AVARD S. EMERY, DECEASED.

STEAM-BOILER.

SPECIFICATION forming part of Letters Patent No. 425,766, dated April 15, 1890.

Application filed April 2, 1888. Renewed February 1, 1890. Serial No. 338,845. (No model.)

To all whom it may concern:

Be it known that I, AVARD S. EMERY, of the city and State of New York, have invented an Improvement in Steam-Boilers, of which the following in a specification.

Boilers for steam-heating apparatus have been made with two cases, with the water between the cases and above the inner casing, there being a steam-space below the top of the outer casing, and in some instances pipes through which the water is allowed to circulate have been within the inner casing; but these pipes are exposed to a greater degree of heat than the casings, and hence the expansion and contraction are unequal and the joints are liable to become loose and leak.

The object of my present invention is to increase the area of surface with which the heated gases come into contact without materially obstructing the draft through the fire, and also to allow for expansion and contraction without the risk of injury to the joints.

In the drawings, Figure 1 is a vertical section of my improved boiler. Fig. 2 is a plan of the lower water-chamber. Fig. 3 is a plan of the second water-chamber; Fig. 4, of the third, and Fig. 5 of the fourth, water-chamber.

The boiler is preferably cylindrical, and composed of an outer casing 1 and inner casing 2, the outer casing being the longest, so as to allow the necessary steam and water space between the top 3 of the outer casing and the top 4 of the inner casing, and the two cylinders are connected together at their lower ends, as shown at 5, and there is an opening at F for the fire-door, as usual, and openings at C for cleaning off the respective chambers and removing dust and soot. The doors for these openings are of any ordinary or desired character, and I prefer to allow the products of combustion to pass out through the vertical flue 6 at the top of the boiler.

I have shown four water-chambers within the inner casing 2. The number, however, may be more or less. Each water-chamber is preferably circular and the top and bottom thereof slightly conical, and these are usually of cast-iron and of such a size that the products of combustion are free to pass between the outer edges of the water-chambers and the interior

of the inner shell or case 2, and through these water-chambers vertical flue-tubes S pass, and these are usually cast with the rest of the water-chamber, and I prefer to make use of flues S in one of the water-chambers, that are 55 nearer to the center of such water-chamber than the similar flues in the next water-chamber above, so that the products of combustion in passing through these vertical flues pursue a tortuous or zigzag course, as indicated by 60 the arrows.

There are central openings with hubs at the top and bottom of each water-chamber, and these are screw-threaded to receive the ends of the iron tubes or thimbles B, by which one 65 water-chamber A is connected to the next, and a tight joint is thereby made between one water-chamber and the next, and the upper water-chamber is provided with hubs at 10, that are screw-threaded for the reception 70 of the iron tubes B', that pass up through holes in the crown or top 4 of the inner case 2, and the joints at these points are made tight by jam-nuts above and below the top 4, and it will be apparent that by these pipes 75 B' and B the range of water-chambers is suspended from the top of the inner case, and it is free to expand and contract, according to the temperature to which it is exposed.

At the bottom of the lower water-chamber 80 A the branch pipe R is connected by an elbow and screw-nipple, and such branch pipe R passes off laterally and freely through an opening 12 in the cases 1 and 2, and then such pipe R is provided with an elbow and descends vertically, and is connected at the outside of the case 1 to the water-space, and at this same place the water of condensation is returned to this boiler or heater, and it passes not only into the water-leg between the cases 85 1 and 2, but it also ascends through the pipe R into the water-chambers A, and passes up through the same and through the pipes B and B' to the water-space at the top of the boiler, and should there be any difference in the 90 expansion or contraction of the cases 1 and 2 and the water-chambers A and pipes B the horizontal portion of the pipe R will spring and allow for this variation without either of the joints being injured or made to leak, and 100

I place around the pipe R at the opening 12 a plate or septum 13, that prevents the escape of gas at this point; but it does not interfere with the slight movements of the parts due 5 to expansion and contraction.

The top of the upper water-chamber A may be provided with a vertical pipe O within the flue-space 6, with lateral branches S' into the steam-space of the boiler, so that any bubbles 10 of steam from the water-chambers A may ascend directly into the steam-space of the boiler and not interfere with the circulation of the water.

I claim as my invention—

- 15 1. The combination, in a heating-boiler, of the cases 1 and 2, connected at their lower ends, the water-chambers A within the inner casing, the pipes B, for connecting one water-chamber with another, the pipes B', for connecting the upper water-chamber with the inner case of the boiler, and the pipe R, connected at the lower side of the bottom water-chamber and passing off horizontally through the opening in the casing, and connected outside the boiler with the vertical pipe that is 20 united at its lower end to the boiler, substantially as set forth.
- 20 25

2. The combination, with a boiler having the cases 1 and 2, with the water space or leg between them, of a vertical range of horizontal water-chambers, each water-chamber having vertical flue-openings passing through the same, and the pipes B, secured into the respective water-chambers and connecting them together, and the horizontal pipe R, connecting the bottom of the lower water-chamber with the shell of the boiler, substantially as set forth.

3. The combination, with the boiler-shells 1 and 2, of a vertical range of water-chambers, each of which has passing through the same vertical flue-pipes, and the pipes B, connecting one water-chamber with the next, the pipes B', connecting the upper water-chamber with the inner shell of the boiler, and the 40 pipe O and branches S' within the flue 6 of the boiler and opening into the steam-space of the same, substantially as set forth.

Signed by me this 24th day of March, 1888.

AVARD S. EMERY.
